DANIEL MCFARLAN MOORE, OF NEWARK, NEW JERSEY, ASSIGNOR TO MOORE ELECTRICAL CO., OF NEW YORK, N. Y., A CORPORATION OF NEW YORK.

ELECTRICALLY-OPERATED VACUUM-TUBE.

1,020,109.

Specification of Letters Patent. Patented Mar. 12, 1912.

Application filed September 2, 1903. Serial No. 171,587.

To all whom it may concern:

Be it known that I, DANIEL MCFARLAN MOORE, a citizen of the United States, and a resident of Newark, in the county of Essex and State of New Jersey, have invented certain new and useful Improvements in Electrically-Operated Vacuum-Tubes, of which the following is a specification.

My invention relates to that class of electric lighting or other devices consisting of a sealed receptacle, usually made completely of glass, containing a gas or vapor rarefied or of any suitable tension, and provided with means for passing an electric current through the interior of the receptacle.

My invention relates more particularly to this general class of devices when organized to produce light by the action of electric current upon the contained gas or vapor, although the invention is not confined thereto. Inasmuch as in this class of apparatus the receptacle is customarily made in the form of a tube, I shall hereinafter refer to the said receptacle as a tube. It is to be understood, however, that the term "tube" is employed as including any form or contour of sealed receptacle.

The principal object of my invention is to increase the life of such devices, especially when used for electric lighting. As applied to X ray tubes and other devices in which the prime purpose is not to produce light, the utility resides principally in the fact that the gas or vapor is maintained at a stable tension.

In describing my invention I shall also assume that the tube is one in which the current is applied electrostatically by means of suitable exterior conducting caps, although the invention is likewise applicable to tubes in which the current is conveyed to the contents by conductors projecting into the interior thereof so as to be in contact with the contained gas or vapor.

In devices of this character, it is found that ordinarily the rarefied gas employed gradually deteriorates under the action of the electric current or, in other words, gradually loses its capacity to give out light so that the life of the lamp is compara-

tively short unless provision be made for supplying fresh gas or restoring the gas to a condition in which it will be capable of emitting light rays through the action of the electric current.

55

Briefly stated, my present invention consists in providing the tube with some solid chemical compound introduced into it in any desired way and so disposed within said tube as to be subject to the decompos- 60

ing action of that portion of the electric current which flows between the electrodes within said tube and gradually release an element suitable for use in a gaseous condition as the rarefied gas or vapor of any 65 suitable tension used within the tube. Preferably I employ in the tube an organic substance by which term I include all substances, animal or vegetable, containing carbon as an essential ingredient. While it 70

would be within my invention to employ any organic substance or compound of which carbon is one of the elements, I prefer to employ a carbon compound resulting from the electrolytic treatment of an organic substance as hereinafter described; and among such organic compounds or substances I use, by preference, those of the hydrocarbon class among which I find that those coming under the head of benzin derivatives are especially suitable. Thus, for instance, the carbon compound employed in the lamp or tube may be obtained by electrolytically treating an aromatic hydrocarbon such as benzin, toluene, etc., or a de- 75

rivative thereof such as anisic, benzoic, (without nitrogen), hippuric acid and benzamid (with nitrogen) $C_{23}H_{18}N_2O_2$. When the organic substance employed in the tube is obtained by electrolytic treatment of another substance, it may be produced in a tube of glass say 4 or 5 feet in length which is provided with suitable caps or electrodes by which electric current of high tension may be passed from one end to the other of 95 the tube to act upon any or all of the contents. Into this tube I introduce the substance to be treated, which in the case of a solid is preferably powdered and introduced into the tube and uniformly distrib- 100

uted by rotating the tube, heat being externally applied when necessary to cause the substance to adhere to the tube. In some cases where the substance to be treated will 5 sublime without decomposition (anisic or benzoic acid) I prefer to place the tube in a slanting position with the substance occupying the lower end, or in a suitable tubular projection, to which heat is applied. The tube fills with vapor, which 10 condenses on the cold walls, and the tube becomes coated internally with the substance employed in a finely divided crystalline condition. If the substance is a liquid, the walls of the tube may be covered with a thin film by introducing the substance into the tube and then rotating the tube while held in a horizontal position. The tube is then sealed up and attached to 15 a vacuum pump which is operated to exhaust the air or other gas used in the treatment and reduce the same to a more tenuous condition while at the same time electric current is passed through the tube in 20 any suitable manner. I find in practice that the exhaustion in many cases hastens the process of conversion of the substance. If desired or necessary, heat may be applied at the same time to the tube to assist 25 in the conversion. In this operation the decomposing effect of the current is accompanied by a change in the color of the gaseous contents of the tube from a red color at the beginning of the operation to a thick 30 white as the exhaustion progresses. This change takes place when the action progresses in the normal and expeditious manner. In the case of some substances, as for instance, crystals of hippuric acid, it may be 35 found that even with the continued application of the current, no apparent decomposing effect takes place and that the light in the tube instead of changing from a red color at the beginning of the operation to a 40 thick white as the exhaustion progresses, changes from a red to a very thin white. In this case it is desirable to apply heat as just stated and the product having the characteristics to be presently mentioned can 45 then be readily secured. By this operation there is produced a fixed solid residue which forms a more or less spongy but still adherent coating upon the walls of the tube extending in some cases in finished tubes 50 for several inches beyond the terminals. The exact composition of the carbon compound resulting from this process is uncertain. In those compounds from which I have obtained the best results, benzamid 55 and in many cases acetamid is present in considerable quantities. When the carbon compound is obtained from the treatment of hydrocarbons like benzoic acid ($C_7H_6O_2$) or anisic acid ($C_8H_8O_3$) or other substance

containing no nitrogen, the amid results 65 from the presence of the nitrogen of the air in the tube while the current is traversing the same. In this operation the production of the coating seems to be assisted by lowering the pressure of the air or other gas 70 within the tube, although as hereinafter described, the same material may be obtained by treating the substance mentioned in the open air, but with less facility. Near the commencement of the exhaustion the light 75 in the tube is a deep red color changing to a pure white, this change in color probably marking the fixation of the nitrogen and the production of the amid or other organic compound having nitrogen for one of its 80 constituents. I also employ pure nitrogen in the place of air for this purpose. The same treatment may be applied to a substance already embracing nitrogen as a constituent, for example, benzonitril, benzamid, 85 acetamid, &c.

While it is possible to use for the purposes of my invention a carbon compound consisting of the substance resulting from the electrolytic treatment of any of the substances already mentioned, I find in practice that excellent results are obtained from the material produced by the treatment of the aldehyde of anise known as aubépin.

The presence of the organic substance 95 within the electrically operated tube for the purpose of my invention, may be secured in various ways. If such substance be one secured by electrolytic action, as already described, the material to be electrolyzed 100 may be introduced into the terminals of the tube to be used in commercial work and a current passed through the tube and contents while exhaustion is going on, thus producing an organic substance or carbon compound of the preferred character within the tube as already described. Secondly: the coating resulting from electrolytic treatment of the material within the tube or receptacle 105 may be scraped off and introduced in suitable quantities into the tube designed for commercial use, after which the latter may be completed by exhausting it, while preferably at the same time passing current through it. Thirdly: a section of tubing 110 containing the carbon compound or substance resulting from electrolytic treatment already described, can be used as a part of a commercial tube. In ordinary cases, the presence of from 3 to 4 grams of the material to 100 feet of tubing more or less will be sufficient. The presence of such an organic substance or carbon compound within a tube secures in the case of a light tube, a smooth or perfectly steady, uniform light 115 with an efficient light for the tube several times as great as that of a similar tube not provided with such compound. It is espe-

- cially useful for external electrode vacuum tubes used for lighting, but is useful for all classes of tubes including X ray tubes and gas or vapor lighting tubes having either internal or external electrodes, by maintaining the vacuum at a stable degree of rarefaction. Another advantage is that a comparatively low vacuum can be used and yet the light is satisfactory in all respects.
- 10 Heretofore, in order to obtain such a light, a high vacuum, comparatively speaking, was absolutely essential and therefore required suitable vacuum pumps for the production of the high vacua, and this involved the use of mercury pumps: but with the chemicals as described the tubes can be exhausted by using only so-called mechanical pumps, that is, various kinds of vacuum pumps that do not employ mercury.
- 15 When my invention is employed for tubes containing a vapor of a metal such for instance, as mercury vapor, it has the additional practical effect of supplying the missing red rays whose absence, in the case of a mercury vapor lamp or tube produces a peculiar and well-known objectionable quality of light, in which respect benzamid is particularly useful as it supplies in a large quantity the missing red rays.
- 20 The carbon compound or organic substance obtained from the electrolytic treatment of an organic material, decomposed by the treatment to its final form and employed according to my invention is of advantage in obviating to a considerable extent the difficulty heretofore met with namely: that the chemicals or materials heretofore used in either solid, liquid or gaseous form, when employed directly in
- 25 light tubes, form by the action of the electric current when the lamp is in use, objectionable spots or discolorations deposited on the inner walls thereof along the light-giving area.
- 30 The exact manner in which the organic substance produced by electrolytic action from the materials mentioned, operates in a tube, I am not able to state precisely. It seems probable that the gases held by the
- 35 solid material are decomposed by the electric current and re-combined by the catalytic action of the spongy residue and since this constantly and rapidly recurring action is nearly perfect, the life of the tube is very
- 40 great, being only limited by the slow breaking down or clogging of the porous residue with a consequent loss of the necessary amount of surface exposed to regenerate the gases as fast as they are decomposed by the
- 45 current. That is, this new material becomes the agent in a train or cycle of actions in which the gases forming the light are decomposed or affected by the lighting current and transformed into a gas or gases
- 50 whose chemical constitution is such that they can from the new substance or material be changed or re-composed into the gas which is effective in producing the light.
- 55 The value of an organic substance of whatever kind and however obtained or produced, contained in the tube, in securing high efficiency and luminosity, I believe to be due to the fact that the carbon being in chemical union with other materials is in a form to be liberated by the electrolytic action as a carbon gas, the atoms of which become ionized and are in fact the seat of the luminous radiations, so that in effect, said carbon gas is the luminous agent of a vacuum tube lamp just as the solid carbon is the 60 luminous agent of an ordinary incandescent lamp. I am led to this conclusion because so far as my experiments show it is not practicable to obtain good results in a vacuum tube lamp by simply inclosing therein solid 65 amorphous carbon, or in other words the element carbon in a form in which so far as experiment shows, it is incapable of being gasified or vaporized. By however using the carbon in a chemical union with other materials and in a substance capable of being electrolytically decomposed, it is then possible to liberate it in a form in which it may be effectually ionized. So far as my 70 experiments show, practically any organic compound is capable of being used in this way, although I prefer to use a solid organic compound since the liquids tend to decompose or vaporize too rapidly, thus preventing the attainment or the maintenance of the desired degree of rarefaction within the tube, when introduced therein for the purpose of supplying fresh gas as the gas deteriorates under the action of the current. Solid materials, or compounds, are free 75 from this objection because they do not so readily vaporize or assume a gaseous condition under the high vacuum and moderate temperature at which the vacuum tubes are 80 ordinarily operated.
- 85 Instead of producing an organic substance or carbon compound from electrolytic treatment of a substance within the tube, the same may obviously be produced in the open air by spreading the material on a suitable 90 plate and then passing the electrolyzing current through it by placing one terminal of the high tension source of electricity beneath the plate and another above it and close to the film or layer of material. This 95 causes high tension sparks to radiate all over and through the chemical causing part of it to evaporate and after some time leaving a residue in the form of a coating on the plate that is similar to that produced 100 within the tube which has a high vacuum pump attached to it. However, I have 105 found that this latter method is far more

laborious, more expensive, and not nearly as desirable as the vacuum process.

As already stated, the exact composition of the material resulting from the process of production hereinbefore described cannot be exactly set forth. In its physical appearance and characteristics such material, when scraped off from the surface on which it is formed or deposited, will appear as a 10 granular, sawdust like substance somewhat resembling brown sugar in appearance but readily reduced by attrition to an almost impalpable powder.

In the accompanying drawings, Figure 1 15 shows a tube or receptacle that may be employed in producing the substance, and at the same time be a part of the light tube; Fig. 2 shows a tube specially designed for preparing the chemical; Fig. 3 shows a tube 20 for introducing the chemical in a modified way; Fig. 4 shows a modified form of apparatus that may be used for producing the substance.

Referring to Fig. 1, 1 indicates a tube 25 preferably of translucent material like glass and having conducting caps for the application of an electric current to the contents of the tube. 4, is a small tube attached to the larger receptacle for the purpose of permitting the contents to be exhausted by the application of an exhaust pump. The oil or other material introduced into the tube 1, if of liquid form, is preferably spread over the interior surface by shaking the tube and the 30 tube is then allowed to drain off after which it is sealed and the current applied and the tube exhausted during the treatment by the electrolyzing current.

Referring to Fig. 2, after treatment of the 40 chemical is completed, which may be judged by the changed appearance of the coating in the translucent section 2, which generally changes to a brown color, the tube is opened and said material may be scraped off and 45 introduced into tubes like 3, Fig. 1, to be sealed to tube 5, which, of course, has an electrical terminal at its other end, and the manufacture of the lamp completed by the exhaustion of the contents to the desired degree of rarefaction in any proper manner. Instead of recovering the material by scraping it from the surfaces on which it is used, it may be washed off by the use of various liquids such as alcohol and then recovered 55 by evaporation.

In Fig. 3, 6 indicates a separate receptacle in which the substance may be placed so that when heated its vapors will pass into and condense on the walls of 7, the exterior of 60 which is coated with graphite or other suitable material which is connected with the wire 8 leading to a source of electricity of suitable potential.

In Fig. 4, 9 indicates a plate upon which

the substance 10 to be treated may be spread, 65 and 11 and 12 the electrodes for electrolyzing said material in one of the manners previously mentioned, viz: in the open air.

In the foregoing specification and annexed 70 claims the term "tube" is used as synonymous with a sealed receptacle of any form or contour.

My invention is not limited to tubes containing only a rarefied gas acting and acted upon as herein described, but may be used 75 with tubes in which there is also a mercury vapor or other metallic or mineral vapor or gas.

The new material or substance resulting 80 from the electrolysis process as hereinbefore described, is not herein claimed, excepting as applied to the interior of an electrically-operated gas or vapor tube for the purposes hereinbefore set forth. Said material or substance as well as the manner of producing 85 the same form the subject of claims in the application for patent filed by me April 21st, 1904, Serial No. 204,174 as a division of the present application.

The particular methods of manufacturing 90 gas or vapor tubes to secure a tube containing the material herein described and claimed are not herein claimed, as they also form the subject of claims in another application for patent filed by me April 21st, 95 1904, Serial No. 204,173 as a division of the present application and patented March 13th, 1906, No. 814,794.

What I claim as my invention is:

1. An electrically operated vacuum tube 100 containing a solid compound of carbon disposed within the tube and in position to be decomposed by the action of the electric energy in its transfer from one to the other of the main or principal electrodes for said 105 tube.

2. An electrically operated vacuum tube containing the product of the electrolysis of an organic substance.

3. An electrically operated vacuum tube 110 containing the product of the electrolysis of a hydrocarbon.

4. An electrically operated vacuum tube containing the product of the electrolysis of a vegetable hydrocarbon. 115

5. An electrically operated vacuum tube containing the product of the electrolysis of an aromatic hydrocarbon.

6. An electrically operated vacuum tube 120 containing the product of the electrolysis of a hydrocarbon known as a benzin derivative.

7. An electrically operated vacuum tube containing an organic substance of which nitrogen is a constituent.

8. An electrically operated vacuum tube 125 containing the product of the electrolysis of aldehyde.

9. An electrically operated vacuum tube

- containing the product of the electrolysis of aldehyde of anise.
10. An electrically operated vacuum tube containing the product of the electrolysis of an organic substance and having nitrogen as one of its constituents.
11. An electrically operated vacuum tube containing a rarefied gas and an amid, as and for the purpose described.
- 10 12. An electrically operated vacuum tube containing a rarefied gas and an organic substance of which nitrogen is a constituent.
- Signed at New York city in the county of New York and State of New York, this 28th day of August A. D. 1903.
- DANIEL McFARLAN MOORE.
